Primary Examiner — Caron D Veynar*Assistant Examiner* — Laura Yu(74) Attorney, Agent, or Firm — Conneely PC; Joseph Conneely(57) CLAIM

The ornamental design for a shirt, as shown and described.

DESCRIPTION

FIG. 1 is a front view of a shirt according to the design;

FIG. 2 is a rear view thereof;

FIG. 3 is a right side view thereof;

FIG. 4 is a left side view thereof;

FIG. 5 is a front perspective view thereof;

FIG. 6 is a rear perspective view thereof; and,

FIG. 7 is a front environmental view thereof.

The broken line showing of the head, neck, arms, hands, and legs in FIG. 7 is for the purpose of illustrating portions of the environmental structure and forms no part of the claimed design.
